CLAIM

The ornamental design for a pneumatic tire, as shown and described.

DESCRIPTION

FIG. 1 is a front elevational view of a pneumatic tire showing my new design, it being understood that the tire tread pattern repeats circumferentially throughout the outer circumference.

FIG. 2 is a perspective view of one side of the pneumatic tire as shown in FIG. 1, wherein the other side is identical to FIG. 2; and,

FIG. 3 is a side elevational view of one side of the pneumatic tire shown in FIG. 1, it being understood that the other side is identical to FIG. 3.

1 Claim, 3 Drawing Sheets

FIG.1

FIG. 2

FIG. 3
